US00D979435S

(12) **United States Design Patent** (10) Patent No.: **US D979,435 S**
(45) Date of Patent: **** Feb. 28, 2023**

(54) **FUEL SENSOR**

(71) Applicant: **nVent Services GmbH**, Schaffhausen (CH)

(72) Inventors: **Wesley Dong**, Belmont, CA (US); **Jennifer Robison**, San Carlos, CA (US); **Emmi Ngo**, Santa Rosa, CA (US); **Peter Wijeratne**, San Carlos, CA (US); **Johnny Lam**, San Mateo, CA (US)

(73) Assignee: **nVent Services GmbH**, Schaffhausen (CH)

(**) Term: **15 Years**

(21) Appl. No.: **29/840,004**

(22) Filed: **May 25, 2022**

(57) **CLAIM**

The ornamental design for a fuel sensor, as shown and described.

DESCRIPTION

FIG. 1 is a perspective view of a front, top, and right side of an embodiment of an ornamental design for a fuel sensor; FIG. 2 is a front side elevational view of the fuel sensor of FIG. 1; FIG. 3 is a rear side elevational view of the fuel sensor of FIG. 1; FIG. 4 is a right elevational view of the fuel sensor of FIG. 1; FIG. 5 is a left elevational view of the fuel sensor of FIG. 1; FIG. 6 is a top plan view of the fuel sensor of FIG. 1; and, FIG. 7 is a bottom plan view of the fuel sensor of FIG. 1. The dash-dash broken lines shown are included for the purpose of illustrating portions of the fuel sensor that form no part of the claim.

1 Claim, 3 Drawing Sheets
